DESIGN FOR A CASING FOR SUCTION CLEANERS OR SIMILAR ARTICLES

Henry Dreyfuss, New York, N. Y., assignor to
The Hoover Company, North Canton, Ohio, a
corporation of Ohio

Application September 11, 1939, Serial No. 87,142

Term of patent 14 years

To all whom it may concern:

Be it known that I, Henry Dreyfuss, a citizen
of the United States, residing at New York city,
in the county of New York and State of New York,
have invented a new, original, and ornamental
Design for a Casing for Suction Cleaners or Simi-
ilar Articles, of which the following is a speci-
fication, reference being had to the accompany-
ing drawing, forming a part thereof.

In the drawing:

Figure 1 is a side elevation of a casing for suc-

tion cleaners or similar articles showing my new
design;

Figure 2 is a front view of the same; and

Figure 3 is a perspective view of the same on a
somewhat enlarged scale as compared to the dis-
closure in Figures 1 and 2.

I claim:

The ornamental design for a casing for suction
cleaners or similar articles, substantially as
shown,

HENRY DREYFUSS.
